UNITED STATES PATENT OFFICE.

JOSEPH RENÉ AYOTTE, OF CHICAGO, ILLINOIS.

HAND-TOOL.

1,395,888.

Specification of Letters Patent.

Patented Nov. 1, 1921.

Application filed March 15, 1920. Serial No. 366,059.

To all whom it may concern:

Be it known that I, JOSEPH RENÉ AYOTTE, a subject of the King of Great Britain, residing at Chicago, in the county of Cook and 5 State of Illinois, have invented certain new and useful Improvements in Hand-Tools, of which the following is a specification.

This invention relates to certain improvements in hand tools, such as wrenches and 10 the like, it being an object to so construct the implement that it may be easily operated and applied to parts that are located in relatively inaccessible places; that it have a longitudinally extensible handle adapted to operate 15 conveniently under different conditions; that it have means for holding a tool socket which is formed specially to coöperate with the parts to be acted upon; and that its 20 component parts be so arranged and combined as to produce a strong, durable, and efficient construction.

This invention further resides in numerous other features of construction and combinations of parts all of which will more 25 clearly hereinafter appear in the specification to follow, wherein reference is made to the accompanying drawing which exhibits an exemplification of this invention in the manner following:

30 Figure 1 shows in side elevation the tool with its operating handle in extended position, the tool socket being shown as detached from the implement;

Fig. 2 is a longitudinal section through 35 the implement, the operating handle being in telescoped position;

Fig. 3 is a detail, principally in elevation, a portion of the view, however, representing 40 a section taken on line 3—3 of Fig. 2; and Figs. 4, 5, and 6 are enlarged transverse sections taken, respectively, on lines 4—4, 5—5, and 6—6 of Fig. 2.

In the embodiment of the invention illustrated on the accompanying drawing, the tool comprises a body in the form of an outer casing A which surrounds a sleeve B within 45 which is an extensible tube C. At its lower end the sleeve is connected as by means of a universal joint 10 with a holder D having a head portion 11 in overlying relation to the proximate end of the casing A, which is 50 preferably bent at an angle relative to the main portion of the tool. Any suitable opening 12 may be formed in the casing 55 bend near the joint 10, as shown, to facili-

tate the assembly and lubrication of the parts inside. At its other end the sleeve B is formed with a head 13 which overlies the upper end of the casing. By means of the holder head at one end and the sleeve head 60 at the other end, the sleeve and holder are maintained as a unit in a fixed longitudinal position within the casing.

Through the medium of the sleeve rotary motion may be communicated to the holder 65 D which is formed to receive a tool or socket member E (see Fig. 1) that is adapted to engage with the work. For this purpose, the holder is preferably formed interiorly with polygonal faces 15 beyond which are one or 70 more annular recesses 16 within each of which is located a spring ring 17. The tool or socket member which coöperates with the holder thus formed is also provided with corresponding polygonal faces 18 so as to fit 75 non-rotatably within the holder, and is further provided with a head on which are formed a plurality of annular grooves 19 each of which may receive one of the spring rings 17 when forced into registering position relative thereto. According to this construction, the socket member may be slipped in and out of the holder against the combined tension of the split rings whose normal tendency is to hold the socket member 80 operatively in position. By employing a plurality of rings and grooves as shown, I provide a more secure fastening for the tool member than would otherwise be possible.

In the operation of the tool, its body is 85 held against rotation while the sleeve B is rotated. This is accomplished through the medium of the tube C which is non-rotatably connected to the sleeve B as by means of a key 20 that is received within 90 a slot 21 formed in the head 13 of the sleeve B. This slot extends downwardly from the upper end of the head close to its shoulder 95 22 which abuts the upper end of the casing A. When the key is slipped in place within 100 the slot, it is confined as by means of a cap 25 which is threaded to screw onto the upper end of the sleeve head 13 as best shown in Fig. 2. Interiorly the cap is formed with a shoulder 26 which overlies the sleeve 105 head as well as the slot 21 therein. Adjacent the shoulder 26 is an annular groove 27 within which is seated a spring ring 28 that is adapted to engage within any one of several annular grooves 29 that are formed ex- 110

teriorly of the tube C. As illustrated in Fig. 2, this spring 28 is seated within the uppermost groove 29 so as to normally maintain the handle in telescoped position as shown. 5 When, however, the handle is extended as shown in Fig. 1, the spring ring 28 will seat within another groove 29 so as to maintain the handle in a definite position of adjustment. Other adjustments, of course, 10 are permissible, depending upon the number and location of the grooves 29 within any one of which the ring 28 coöperates by friction to maintain the parts in certain relative positions. The tube C is provided 15 also with a longitudinal groove 30 into which the key 20 projects so as to prevent relative rotary movement between the tube and sleeve B, regardless of the distance to which the tube may have been extended longitudinally thereof. This groove may be 20 conveniently formed by constructing the tube of two parts—an inner sleeve 31 around which is wrapped a plate 32 having its meeting edges slightly spaced apart to form the groove 30. This plate 32 may be 25 conveniently welded to the sleeve 31 so that the tube C, to all intents and purposes, represents an integral construction.

The construction thus far described 30 provides for a driving connection between the tube C and the socket member E regardless of the longitudinal adjustment of the tube relative to the casing. Other means for imparting rotation to the tube are also provided which preferably consist of a stud 35 non-rotatably locked to the tube C as by means of a cross pin 36, this stud extending exteriorly beyond the cap 25 and having a head 37 by which is secured to the cap and tube C a hub 38. Within the hub is formed 40 a recess 40 that encircles the stud and which receives a toothed wheel 41 that is locked to the stud as by means of a cross pin 42. Within this same recess 40 are mounted a 45 pair of dogs 43 each pivoted as at 44 to swing into or out of engaging position relative to the teeth of the wheel 40 for the purpose of actuating the same in either or both directions. These dogs are held in either 50 operative or inoperative position as by means of a spring 45 which is secured in place by a pin 46, the spring having two arms one of which is in operative relation with each dog. The operative relation of 55 the dogs to the wheel is of the usual kind to provide a ratchet working one or both ways, depending upon which dog is engaged with the wheel.

Extending laterally from the hub 38 is an 60 arm 48 that is socketed to receive the end of an operating lever 50 which may be of any convenient size and shape. As shown in the drawing, the end of the lever which fits within the arm socket is grooved as at 65 51, a second groove 52 being formed in the

arm to retain therewithin a spring ring 53 which coöperates with the groove 51 to maintain the lever in place. It may be desirable that the crank have its free end 54 laterally turned to facilitate use of the tool, 70 and the construction that I have shown between the crank and arm is such as to permit the lever to turn about its own axis while still maintaining connection with the 75 handle.

I would have it understood, however, that in lieu of a single groove 52 and spring retained therein, two or more such grooves or springs might be used to supplement the locking connection. Also, if preferred, another form of connection might be used, such, for instance, as an ordinary screw-thread, to maintain the lever in operative relation to the handle.

The implement that I have described is 85 exceedingly simple in its construction, and in the operations which are requisite to its use. The character of lock which maintains the handle in any given longitudinal position of adjustment relative to the body is 90 such as to require merely the exercise of sufficient force to overcome the tension of the split spring ring that is used, and, if preferred, this tension may be augmented by the use of two or more springs should 95 this be found desirable. It is manifest, of course, that the tool may be constructed to any desired proportions and of any suitable materials. Changes or modifications may 100 obviously be made without sacrificing the features of advantage herein described, and in so far as such constructions answer to the claims of this invention as defined below, I desire that they be included within the scope of this patent.

I claim:

1. A tool of the kind described having, in combination, a body, a sleeve rotatably mounted therewithin, a holder carried at one end of the sleeve, a tool socket fitted 110 within the holder, and means extensible longitudinally of the tool for rotating the sleeve comprising a tube adapted to telescope therewithin and having thereon a plurality of annular grooves, means detachably secured to the sleeve within which is formed a seat, a split ring arranged within the seat and adapted to engage frictionally within any one of the annular grooves in the tube for maintaining the latter in a definite position longitudinally of the sleeve, and a driving connection between the tube and sleeve operative in all relative positions of adjustment between these parts.

2. A tool of the kind described having, in 125 combination, a body, a sleeve rotatably mounted therewithin, a head at one end of the sleeve in overlying relation to the body and formed on its inner side with a slot, a tube telescoped within the sleeve and having 130

a slot formed longitudinally thereof as well as a plurality of grooves arranged annularly thereon, a key disposed within the slot in the sleeve head and in the other slot within the sleeve head and in the other slot within the tube to establish a driving connection between the tube and sleeve, a cap detachably secured to the sleeve head and forming a closure for the slot in which the key is retained, the cap when detached from the sleeve head permitting removal of the key, and a spring friction device carried by the cap adapted to engage within any selected groove in the tube to maintain the latter in a definite position of adjustment longitudinally of the sleeve, substantially as described.

3. A tool of the kind described having, in combination, a body, a sleeve rotatably mounted therewithin, a head on one end of the sleeve in overlying relation to the body, a slot in the head, a holder associated with the other end of the sleeve and disposed in overlying relation to the other end of the body, a tube extensibly secured within the sleeve having a slot on its outer surface registering with the slot in the head, and having a driving connection with the sleeve comprising a key that is seated within the two registering slots, a cap detachably secured to the sleeve head forming a closure for the slot in which the key is received, and spring means carried by the cap adapted to maintain the tube in different positions of longitudinal adjustment relative to the sleeve, a hub arranged exteriorly of the cap, a stud connecting the hub nonrotatably to the tube, a lever projecting from the hub and adapted to effect rotation thereof, and ratchet mechanism for establishing a driving connection between the hub and stud

operable in either direction only, or both, substantially as described.

4. A tool of the kind described having, in combination, a body, a sleeve rotatably mounted therewithin, a holder connected with one end of the sleeve, means for rotating the sleeve comprising a tube extensibly secured therewithin and formed of two parts—one interiorly in the form of a sleeve, and another exteriorly in the form of a plate wrapped around the sleeve with its edges slightly spaced apart to form a slot that extends longitudinally of the tube—and a key locked within the sleeve and projecting into the groove for maintaining a driving connection between these parts, substantially as described.

5. A tool of the kind described having, in combination, a body within which is a rotatable sleeve one of whose ends is in the form of a head in overlying relation to the body, there being a slot formed on the inner side of the head opening onto its outer end, a tube telescoped within the sleeve and having a slot formed longitudinally thereof, a key disposed within the slot in the sleeve head and in the other slot within the tube to establish a driving connection between the tube and sleeve, a cap detachably secured to the sleeve head and forming a closure for the end of the sleeve in which the key is retained, the cap when detached from the sleeve head permitting removal of the key, and means for holding the tube in a definite position of adjustment longitudinally of the sleeve, substantially as described.

JOSEPH RENÉ AYOTTE.
